MATTRESS

Max Koenigsberg, Highland Park, Ill., assignor to The Englander Company, Inc., Chicago, Ill., a corporation of Delaware

Filed Oct. 23, 1958, Ser. No. 53,113

Term of patent 14 years

(Cl. D5—2)

Fig. 1 is a perspective view of a mattress embodying my new design;

Fig. 2 is an enlarged detail view of a portion of the mattress border structure; and

Fig. 3 is a sectional view on the line 3—3 of Fig. 2.

A dominant feature of my design is in the appearance produced by the stitching as shown wherein the appearance is one of substantially closed but communicating rectangles standing diagonally on an edge.

I claim:

The ornamental design for a mattress, substantially as shown and described.
